NESOTA

INSERT-PRINTING DEVICE

Application filed December 24, 1927. Serial No. 242,420.

This invention relates to printing devices and especially to a printing device adapted to be utilized for insert printing.

In many businesses it is necessary to type or print tables, values or other matter in different spaces or panels located in different positions on a variety of different forms or sheets. For example, insurance companies have a multiplicity of different policy forms, 10 each of which is provided with a blank for the insertion of printed matter. Many of the policy forms have said blanks or panels disposed in different positions upon the sheet and, of course, different printed matter is 15 used for each form of policy and moreover for the different ages of each form of policy. The blanks referred to are filled out at the home office of the insurance company and heretofore the values and tables have been 20 typed by a stenographer. As a consequence errors have often been made in filling out some of the values and tables and the insurance company has, of course, been bound by the values enumerated. Such methods have 25 moreover been slow and expensive, requiring in addition to the typing of the tables or values careful checking.

Our invention has for an object to provide a comparatively simple but highly efficient 30 machine or insert printer which may be employed for printing in values, tables or other printed matter in differently arranged spaces or panels on forms or other relatively large sheets.

35 It is a further object to provide an insert printing device, wherein printed plates varying extensively in size and shape may be utilized to print various matter in a variety of different positions with reference to a sheet.

40 Another object is to provide in an insert printer a comparatively simple means for handling a multiplicity of plates of different size and shape and for adjusting said plates in various different positions to properly fill the desired spaces or panels in different forms or sheets.

45 Another object is to provide in a device of the class above described, means whereby an operator knowing the identity of the particular form or sheet to be printed may readily

and easily adjust the device and choose the proper plate to print the desired matter in the proper place on the form or sheet.

Still a further object of the invention is to provide a device of the class described, which 55 will obviate all chances of error which are common where other methods have been used.

These and other objects and advantages will be apparent from the following description made in connection with the accompanying drawings in which like reference characters refer to similar parts throughout the several views and in which,

Fig. 1 is a perspective view of an embodiment of the invention designed for printing in 60 tables and values in insurance policies, the swingable platen frame being shown in partially open position and an insurance policy being shown applied over the plate for printing;

Fig. 2 is a horizontal section taken through 65 the platen frame and showing the toggle structure;

Fig. 3 is a vertical longitudinal section 70 taken through the platen frame;

Fig. 4 is a vertical cross section taken on 75 the line 4—4 of Fig. 3, a portion of one of the toggle links being broken away;

Fig. 5 is a plan view of the adjustable plate bed with a plate thereon, a portion of the 80 printing ribbon being broken away;

Fig. 6 is a vertical section on a larger scale 85 through the platen and the base of the press, showing the adjustable plate bed in side elevation;

Fig. 7 is a vertical section taken on the line 7—7 of Fig. 5 showing the ribbon winding 90 reel;

Fig. 8 is a vertical section taken on the line 8—8 of Fig. 5 showing the opposite end of the 95 ribbon frame with the ribbon spool mounted thereon;

Fig. 9 is a fragmentary plan view of the ratchet and pawl winding mechanism for the ribbon, some portions being shown in section;

Fig. 10 is a detail view showing the means 100 for yieldingly holding the ribbon winding pawl in operative or non-operative position; and

Fig. 11 is a view illustrating a portion of an insurance policy showing a specimen of the work which our device is capable of doing, the table printed being the non-forfeiture 5 values of the policy.

In a general way our invention comprises 10 efficient pressure mechanism adapted to operate upon plates varying in size and shape and disposed in different positions; an efficient adjustable plate bed adapted to hold electro- 15 plates or other plates varying in size and shape; infallible indicating means to clearly show the various positions of the adjustable bed for printing various forms and specially 20 constructed plates adapted to co-operate with the movable bed to cause matter to be printed in the desired positions on the forms.

Our machine may be mounted on any heavy 25 horizontal support, and as shown is mounted upon a cabinet provided with a horizontal top T and also having plate compartments C in which a multiplicity of plates for various forms may be kept for convenient use. Our device may include a heavy printing base 13 which may be embedded or countersunk in 30 the top T of the support. At the rear end of base 13 an upstanding vertical post 14 is rigidly mounted as shown carrying at its lower end a collar 15 carrying at its upper 35 surface a ball race. We provide an elongated platen frame 16 having a heavy bearing at its rear end and set edgewise relatively to the base 13. Platen frame 16 is swivelly connected to post 14. The lower end of the 40 bearing portion referred to, rests upon said ball race. Spacing collars 17 are fixed to post 14 engaging the upper end of bearing portion 16^a. A diagonally disposed brace 18 provided with a turn buckle 18^a connects the intermediate portion of platen frame 16 with the top of post 14, being secured to the top 45 of said post by means of a swivel member 18^b. Platen frame 16 is preferably of hollow construction having parallel vertical sides, provided with a lower open side having rectilinear edges and a closed and concave upper side. As shown, the vertical sides of platen frame 16 are provided with relatively large 50 apertures to facilitate the attachment of the toggle mechanism and within said frame a relatively heavy depending stud 16^b is provided for the purpose of pivotally anchoring the toggle operating bar 19. The forward end of the swingable platen frame may be 55 provided with a handle 16^c and an arcuately and transversely extending notch 16^d of T-shaped cross section is formed in the lower portion of the forward end adapted to interlock with an upstanding complementary 60 shaped rail segment 20 rigidly secured to the forward end of the printing base 13, said interlocking taking place when frame 16 has been swung into position to print. As illustrated, rail segment 20 is provided with a 65 small stop 20^a to limit movement of the platen

frame thereover in one direction and to properly align the platen for printing.

We prefer to provide an elongated substantially rectangular platen P having a pair of upstanding parallel bars 21 disposed edge-wise to platen P, said bars having their ends slidably mounted within the lower portion of the platen frame 16. The movement of said platen P is effected by means of a highly efficient toggle mechanism eccentrically connected with bar 19. Said toggle mechanism comprises a pair of upwardly extending links 22, one pivotally connected to each end of platen P, the lower pivots for said links extending transversely of platen P and journaled in the parallel bars 21. Links 22 have their upper ends pivotally connected to a pair of links 23 of substantially equal length and with the upper ends of links 23 being pivotally connected with the upper portion of platen frame 16 by means of horizontal pivot members 23^a traversing the vertical sides of platen frame 16. The pivotal connection between the links 22 and 23 may be made by means of pins 24, said pins passing through links 22 and 23 and also through the ends of bifurcated members 25, members 25 having inwardly projecting tongues 25^a which are eccentrically connected with the toggle operating bar 19 by adjustable connection members 26. Bar 19 works through one of the apertures in the sides of platen frame 16 and is pivotally secured on a vertical axis to the depending stud 16^b of the platen frame, the pivotal connection being made by a relatively heavy bolt 27. As shown, connection members 26 are provided with suitable turn buckles and bifurcated ends, one of said connection members being pivoted at its inner end to the inner end of bar 19 at one side of the pivot member 27 and said other connection member being pivoted at its inner end to toggle operating arm 19 at the opposite side of pivot 27. As shown in Fig. 2, connection members 26 extend substantially parallel and eccentrically connect the two sets of links 22 and 23 with the bar. A strong coiled spring 28 is interposed between the inner extremity of arm 19 and a retaining member 29 fixed adjacent the forward end of platen frame 16, said spring normally holding bar 19 in rearward position with the platen P elevated. The under surface of platen P is preferably covered with a relatively soft facing 30.

Printing base 13 is preferably provided with a pair of parallel spaced elongated guides 31 between which an adjustable printing bed B is mounted. Bed B as shown comprises a rectangular member having a flat upper surface and a corrugated lower surface, the lateral edges of said member engaging the guides 31. As shown, the bed B is provided at its left side with a rectilinear guide or abutment 32 extending parallel with its left lateral edge 130

and is provided at its upper or rear longitudinal edge with a plurality of spaced upstanding abutment pins 33 extending across bed B in a line perpendicular to abutment 32, said pins being adapted to engage the upper edge of a printing plate and in co-operation with abutment 32 being adapted to hold the several plates in proper position for printing.

10 Bed B carries above its upper surface a ribbon frame 34 of open rectangular structure, said frame being of somewhat larger dimensions than said bed and having its longitudinal sides projecting beyond its lateral sides and turned about a ribbon roller shaft 35 at the left end of the frame and about a ribbon spool shaft 36 at the right end of the frame. Shaft 35 is frictionally and rotatably mounted between the outer ends of a pair of lugs 37 secured at their inner ends to the longitudinal sides of bed B, while the right hand side of the frame is free in order that frame 34 may be swung on shaft 35.

15 Shaft 36 may have a split portion adapted to receive the printing ribbon R. Said ribbon is stretched under a pair of guide members 38, one disposed adjacent each end of the frame and over the bed and a plate X properly disposed on said bed. Ribbon R has its 20 opposite end connected to a winding roller 39 rigidly connected with winding shaft 35 and a ratchet wheel 40 is fixed to the forward extremity of shaft 35 adapted to be actuated by a small pawl 41 pivoted to the adjacent 25 longitudinal edge of ribbon frame 34. Pawl 41 as shown in Figs. 9 and 10 is resiliently held in engagement with ratchet 40 by means of a spring pressed ball 42 housed within said last mentioned longitudinal side of ribbon frame 30 34. Pawl 41 is provided with a pair of inwardly disposed notches or detents 41^a in either of which ball 42 may be seated to either cause said pawl to engage said ratchet 40 or to be held in inoperative position relative 35 thereto as desired. It will be apparent that when the frame 34 is swung open to remove or install one of the plates X the upward swinging movement of said frame will cause ratchet wheel 40 to be turned, moving the ribbon R 40 slightly from right to left.

45 The plates X are made up in different sizes and shapes to suit the requirements of the different forms or policies on which the printing is to be done. The form or policy F is 50 always held in a certain position by means of suitable guiding and retaining means 43, which may be secured to the top of the cabinet or table T. If the panel to be filled with printing is disposed adjacent the left of one 55 of the pages of form F plate X may be made with the characters disposed adjacent the left of the plate or covering the entire plate, as shown in Figure 5. If on the other hand, the panel to be printed is disposed at the right 60 hand side of the sheet the plate X may be

made having a blank portion at the left thereof and having the characters disposed adjacent the right portion of the plate. Thus, it will be seen that assuming the plate to be properly constructed the characters will always be disposed in the proper position to be adjusted to print within the panel by sliding bed B to proper position. In other words, the position of the printed matter on the form between extreme left and right positions depends upon the construction of the particular plate used, since said plate is always held with two of its adjacent edges abutting guide 32 and abutment pins 33, while the position of the plate with reference to the top and bottom of the form is determined by adjusting slideable bed B. We provide one of the plates X for each form or policy and identify each plate in each form with a number or other indicia. As shown, the form and plate is identified as "Endowment at 85, age 35".

70 Efficient indicating means for accurately showing the proper position of the plate bed for printing the different forms may consist in an indicating arm 44 rigidly fixed to one of the longitudinal edges of plate bed B and extending outwardly and from right to left, terminating in an indicating finger or fingers 44^a. For convenience, when the device is used for printing a multiplicity of forms, a plurality of the fingers 44^a are provided, said fingers being adapted to respectively overlie or point to a plurality of parallel columns 45, which may be fixed to the left hand guide member 31 or to the supporting surface T, 75 extending perpendicularly to the longitudinal edges of bed B. In said columns indicia is represented corresponding to the indicia of the several plates and said indicia is set at proper points in said columns to cause the particular plates identified to be disposed in proper position relatively to the top and bottom of the form to be printed for properly printing the matter in the appropriate panel or blank of the form.

Operation

75 The operation of our improved insert printer may be briefly described as follows:—

80 When it is desired to print an insert in a form or policy the plate bearing the identification of the particular form or policy to be printed is withdrawn from the cabinet C, the ribbon frame 34 is swung to open position and said plate is then disposed upon the bed B 85 with its left and upper edges engaging abutments 32 and 33 respectively. Bed B is then moved longitudinally of the printing base 13 until the appropriate indicating finger 44^a is 90 disposed in registration with the identification of the particular plate and form utilized. The plate is then disposed in exact position to print within the blank or insert panel of the form. The ribbon frame 34 is 95 then swung to printing position over plate X 100

115

120

125

130

and the form or policy is disposed above the ribbon frame, held in proper position by abutment engagement with the guiding and retaining means 43 fixed to the supporting surface T. The operator then may grasp handle 16^e of the platen frame swinging said frame to extreme left position, at which time the forward end of the frame is securely interlocked with the rail segment 20 and abuts the small stop member 20^a. Platen P is then positioned directly above the bed B and the bar 19 may be pulled toward the operator to depress the platen and effect the printing upon the under surface of the form.

15 It will be noticed that the toggle structure provided causes a tremendous force to be exerted upon platen P, powerful leverage being obtained through the eccentric connections 26 and further through the leverage 20 upon the toggle links 22 and 23. In the embodiment of the invention commercially manufactured at this time we have found that an operator exerting the force of twenty five pounds upon bar 19 may effect a pressure of 25 over fifteen tons upon the platen P. It will also be noticed that pressure upon the platen is increased as the toggle links 22 and 23 approach dead center position. This increased leverage is desired for printing. The platen 30 actuating mechanism in reality constitutes a double toggle for each end of the platen, the connections 26 with members 25 constituting sets of toggles pivoted on vertical axes, while the toggle links 22 and 23 are pivoted on horizontal axes.

As above described, it will be seen that the operation of inserting the print in the bed, swinging the platen frame and printing occupies extremely short time. To remove the 40 form or policy it is only necessary to swing the platen frame to extreme right position, lift the form from its retaining means 43, and place the plate X utilized in its proper position in cabinet C.

45 At the time of inserting the print in the bed, ribbon frame 34 is swung to open position, thereby actuating through pawl 41 the ratchet 40 and thus causing the ribbon R to be wound slightly upon the winding roll 39. 50 Winding shaft 35, as well as the spool shaft 36 are frictionally held in such a manner that they may be turned by the positive action of pawl 41 upon ratchet 40, but will not slip in the closing movement of the ribbon frame. 55 When the winding of the ribbon on spool 39 is nearly complete pawl 41 may be moved to inoperative position, the spring pressed ball 42 engaging the appropriate detent 41^a and the ribbon may be re-wound upon spool shaft 36 by the manipulation of a knurled knob 36^a rigidly connected to one end of spool shaft 36 or a new ribbon may be supplied if needed.

55 Since the electroplates X contain all the type characters necessary to entirely fill the insert panel of the form, there is no chance of

error in any of the values of characters printed, assuming the proper plate be chosen and the chance of choosing the wrong plate is negligible since the identification of the plate is prominently printed upon the insert, upon the form, and upon one of the indicating columns 45.

70 From the foregoing description it will be seen that we have invented a simple but highly efficient insert printer, capable of quickly and accurately printing in values, characters, etc., in insert panels of forms.

75 It will, of course, be understood that various changes may be made in the form, details, arrangements and proportions of the 80 parts without departing from the scope of the invention.

What is claimed is:

1. In a printing device, a printing bed, a platen frame, a platen slidably carried by 85 said frame, toggle mechanism mounted in said frame for actuating said platen comprising a pair of toggle links, one of which is pivoted on a substantially horizontal axis to said platen, the other of which is pivoted on a substantially horizontal axis to said platen frame, a toggle operating bar pivoted on a substantially vertical axis, and a member eccentrically connecting the common pivot of 90 said toggle links with said operating bar. 95

2. In a printing device, a printing bed, a platen frame, a platen slidably carried by said frame, toggle mechanism mounted in said frame for actuating said platen, comprising a pair of toggle links, one of which is pivoted on a substantially horizontal axis to said platen, the other of which is pivoted on a substantially horizontal axis to said platen frame, a bifurcated member connected to the common pivot of said toggle links, a toggle operating bar pivoted to said platen frame on a substantially vertical axis, and a connecting member having one of its ends eccentrically pivoted on a substantially vertical axis to said 100 toggle operating bar and having its other end pivoted on a substantially vertical axis to said bifurcated member. 105

3. In a printing device, a printing bed, a platen frame, a platen carried by said frame for substantially vertical sliding movement therein, a pair of toggle links disposed above each end of said platen loosely connecting said platen with said platen frame, said links having their pivots disposed substantially horizontally and parallel, a toggle operating bar pivoted to said frame on a substantially vertical axis and having its inner end extended somewhat beyond its pivot and connecting members eccentrically connecting the common pivots of said two sets of toggle links 120 to said toggle bar. 125

4. In a printing device, a printing base, a platen adapted to overlie said base, means for depressing said platen, relatively fixed means for holding a sheet to be printed and a plate 130

holding bed slidably mounted on said base for disposition in various positions relative to the sheet to be printed.

5. In a printing device, a substantially horizontal printing base, a plate holding bed slidably mounted on said base, a platen adapted to be disposed above said base and of sufficient area to overlie said bed in any position thereof relative to said base, and means for retaining the sheet to be printed in a fixed position above a plate on said bed.

6. In a printing device adapted to print relatively small inserts on a sheet, a substantially horizontal printing base, a plate holding bed slidably mounted on said base, a relatively fixed means for holding a sheet to be printed in a predetermined position relative to said base, a printing plate adapted to be mounted in said bed, said printing plate having raised printing characters in a portion thereof, said portion of said plate when said plate is mounted on said bed being substantially alined with the insert space of said sheet, whereby said portion may be brought into exact registration with said space by properly adjusting said bed relatively to said printing base.

7. In a printing device adapted to print relatively small inserts on a sheet, a substantially horizontal printing base, an adjustable bed slidably mounted on said base, means on said bed for positioning two adjacent edges of a plate in a predetermined position with respect to said bed, relatively fixed means for holding the sheet to be printed in a predetermined position relatively to said base, and a printing plate having raised printing characters on a portion thereof, said portion of said plate when said plate is mounted on said bed being substantially alined with the insert space of said sheet, whereby said portion may be brought into exact registration with said space by properly sliding said bed to a certain position relatively to said printing base.

45. 8. In a printing device, a plate holding printing bed, a platen adapted to overlie said bed, means for operating said platen, a ribbon frame hinged to said bed and adapted to overlie a plate on said bed when disposed in substantially horizontal position, a ribbon extending across said ribbon frame and means for moving said ribbon slightly each time said ribbon frame is swung.

55. 9. In a printing device, a substantially horizontal support, a platen frame, pivoted adjacent one of its ends to said support for swinging movement on a vertical axis, a printing bed disposed eccentrically of said axis, a platen disposed medially of said platen frame and adapted to overlie said printing bed when said frame is swung to a predetermined position, retaining means at the free end of said platen frame and cooperating retaining means on said support disposed outwardly of said printing bed for

automatically securing the free end of said frame to said support against upward displacement when said frame is swung to printing position.

10. The structure set forth in claim 9, 70 wherein one of said retaining elements is provided with a groove of T-shaped cross section disposed concentrically of said axis, and wherein said other retaining element constitutes a member of T-shaped cross section disposed concentrically of said axis and one of said elements including means for limiting the swinging movement of said platen frame. 75

11. In a printing device, a printing base, relatively fixed means for holding a sheet to be printed, a plate holding bed slidably mounted on said base, a platen adapted to be disposed above said base, a printing plate having printing characters thereon, the space occupied by said printing characters being positioned a predetermined distance from one edge of said plate to correctly aline said characters laterally for printing in a predetermined position on a sheet, the slidability of said plate holding bed permitting said printing characters to be properly alined longitudinally of said sheet. 90

12. In an insert printing device, a substantially horizontal printing base, a plate holding bed slidably mounted on said base, means on said bed for positioning two adjacent edges of a printing plate in a predetermined position, indicating means on said printing base and indicating means on said slideable printing bed adapted to co-operate with said first mentioned means to indicate the exact positions of said plate bed relatively to said base for printing different forms. 95

13. In an insert printing device, a substantially horizontal printing base, a printing bed slidably mounted on said base for horizontal rectilinear movement within limits, and a compressible horizontal platen mounted above said base and of such area as to cover said base in all positions thereof. 105

In testimony whereof we affix our signatures.
